OSBORNE McDANIEL, OF NEW YORK, N. Y.

Letters Patent No. 78,110, dated May 19, 1868.

IMPROVED FRUIT-BASKET.

The Schedule referred to in these Letters Patent and making part of the same.

TO ALL WHOM IT MAY CONCERN:

Be it known that I, OSBORNE McDANIEL, of New York, in the county and State of New York, have invented a new and improved Fruit-Basket; and I do hereby declare that the following is a full, clear, and exact description thereof, which will enable those skilled in the art to understand and use the same, reference being had to the accompanying drawings, forming part of this specification, of which—

Figure 1 represents a pattern or plan of my fruit-basket.

Figure 2 represents a view of the basket partially made, with the two middle flaps turned up, to form the sides.

Figure 3 represents a view of the basket, with the two main or side flaps turned up, forming the two other sides.

Figures 4 and 5 represent basket complete.

Similar letters indicate corresponding parts.

This invention relates to an improvement in the manufacture of baskets, and consists in a new mode of constructing and forming a box or basket with wood shavings, scales, or veneers, especially adapted to the purpose of transporting berries and small fruits to market. The object of this improvement is economy in construction, to supply the demand for large numbers of berry-baskets at the cheapest possible price. Wood scales, or veneers cut around a log are the cheapest material that can be used for this purpose, and have, I am aware, been employed for making berry-baskets, but my improved method of construction takes less material, as the pattern cuts without waste, and the basket or box is very simple and easily made. It is formed of one single piece of veneer, or other suitable material; the pattern is cut out by a die in such manner that the sides or walls of the basket are formed, in part, by bending or turning up two opposite middle flaps, while the other two sides or walls are formed by bending or turning up two other main outside flaps, and two corner sub-flaps are then bent or turned around to meet or lap upon each other over the two first bent middle flaps, to be fastened by metal tacks, or glue, or otherwise, and thus form the basket or box, with bottom and sides complete, out of one single piece.

For bending the veneer without cracking or breaking, the wood is steamed, or may be cut on one side in the line of the bend, as usual.

The basket is made rectangular in plan, the sides being either inclined or perpendicular to the bottom, and the square form, with inclined sides, is preferred.

The pattern is shown in fig. 1 for a square plan and inclined sides, in which A A represent the two middle flaps that are to be bent or turned up in the lines a b to form two sides or walls of a basket, as clearly seen in fig. 2. B B are two main outside flaps that are bent or turned up in the lines a a, b b, to form the two other sides of the basket, which lines run with the grain of the wood properly, and as seen clearly in fig. 3. At the corners or ends of the main flaps B B are sub-flaps marked 1 1, 2 2, which are bent around in the lines a c, b c, to lie flat against the sides or walls A A, and meet or lap upon each other either in the inner or outside, as shown clearly in fig. 4. The sub-flaps can be fastened with tacks or glued upon the sides A A.

At the intersections of the lines a a, b b, in the corners of the bottom, C, the ends of the cuts a b, a d are enlarged, as shown in figs 1 and 2, more or less, in order to allow the flaps B B to bend on a curve with the grain of the wood, for the purpose of preventing the wood from splitting when bent, and cracking when it shrinks.

And in order to make the edges of the basket or box even, it is necessary to provide for shrinkage of the wood, when bent green or wet, by making the sides or flaps B B wider in the plan or pattern, when cut out, than the flaps A A, by an eighth or quarter of an inch, more or less, according to the nature of the wood or the size of the box or basket, as indicated by the dotted lines e e, figs. 1 and 2.

The box or basket is made on a form, or otherwise, to bend the flaps, and their edges are then brought even all around; those of B B being in line with those of A A, to let the excess of wood be taken up in the curve of the flaps B B, which thus are bent freely without splitting, as shown in figs. 4 and 5, while the shrinkage of the wood in drying is thus also fully provided for, so that it shall not crack.

My improved veneer berry-basket or box admits of various modifications in minor details of construction, but the essential feature of my invention consists in cutting away the bottom corners of the flaps for forming the sides, and thus separating the side-flaps B B from the end-flaps A A, in such manner that the side-flaps can bend with the grain freely upon a full curve, with an excess of wood, when green or wet, to allow for shrinkage in drying, without cracking or splitting.

The subject of my invention is, therefore, the application of the principle of bending the side-flaps with the grain of the wood in such manner that the shrinkage is provided for, whereby the wood shall remain sound when dry or seasoned. This effect is produced by enlarging or cutting away the space between the end and side-flaps A A and B B, securing thereby perfect freedom of the side-flaps in bending with the grain, whereas if this provision is not made in the manufacture of the box or basket made of wood veneers, and the side-flaps are bent with the grain short or rigidly, they will crack or split in drying, and thus render the box worthless.

For the purpose of my invention, the sub-flaps 1 1 and 2 2 may be cut away, to separate them as much and widely as desired from the end-flaps A A, and they may be cut broad or narrow, or be entirely cut off from the main side-flaps B B, in which case the flaps or sides of the box or basket can be fastened by means of strips nailed around the top.

Ventilation is necessary for berries, and I provide for it by perforating the sides or bottom of the basket, the holes or slits being made, when the pattern is cut, by a die. To stiffen the basket, it may be banded around the edge with wood or metal.

Having described my invention, I claim, and desire to secure by Letters Patent—

1. The improved fruit-basket or box made of one piece of veneer, having the flaps cut out at the corners, substantially as described, and bent in a curve with the grain of the wood, so as to prevent splitting in bending, and to provide for shrinkage, as herein set forth.
2. In a fruit-box made of a single piece of veneer, as described, I claim bending two sides with the grain of the wood, when green or wet, in such manner that there shall be an excess of wood in the curve, to provide for the shrinkage of the wood in drying or seasoning.

O. McDANIEL.
